FIG.1.

FIG.2.

FIG.3.

FIG. 4

FIG. 1 is a top plan view of a combined container and artificial fingernails showing my new design in an open condition wherein the lid is hinged at the rear;

FIG. 2 is a front elevational view thereof;

FIG. 3 is a side elevational view thereof; and

FIG. 4 is a top perspective view of an embodiment of my new design wherein the lid is hinged at the sides.

The top, bottom and sides of the container are of flat planar configuration.

This is a division of design applications Ser. Nos. D. 9,451 and D. 9,453, both filed Nov. 17, 1967, and both now abandoned.

I claim:

The ornamental design for combined container and artificial fingernails, as shown and described.
